US00D557264S

(12) **United States Design Patent** (10) **Patent No.:** **US D557,264 S**
Richardson et al. (45) **Date of Patent:** **** Dec. 11, 2007**

(54) **ALPHANUMERIC KEYPAD**

(75) Inventors: **Curtis R. Richardson**, Fort Collins, CO (US); **Jamie L. Johnson**, Fort Collins, CO (US); **Alan Morine**, Fort Collins, CO (US); **Douglas Kempel**, Fort Collins, CO (US); **Dan Hoekstra**, Lafayette, CO (US)

(73) Assignee: **Otter Products, LLC**, Fort Collins, CO (US)

(**) Term: **14 Years**

(21) Appl. No.: **29/246,912**

(22) Filed: **May 19, 2006**

(51) LOC (8) Cl. **14-02**

(52) U.S. Cl. **D14/399**; D14/398

(58) Field of Classification Search ..... D14/391-399, D14/455; D18/1, 2, 7, 11, 12.2; 178/17 A, 178/17 C; 200/5 A, 5 R, 6 A, 6 R; 235/145 A, 235/145 R; 345/160, 168, 169; 341/22, 341/23; 400/484-489, 492; 361/680-686; 257/751

See application file for complete search history.

(57) **CLAIM**

The ornamental design for a alphanumeric keypad, as shown and described.

DESCRIPTION

FIG. 1 is an isometric view of a alphanumeric keypad showing my new design.

FIG. 2 is a front view thereof.

FIG. 3 is a bottom view thereof.

FIG. 4 is a left side view thereof.

FIG. 5 is a right side view thereof.

FIG. 6 is a rear view thereof; and,

FIG. 7 is a top view thereof.

The broken line portions of the disclosure are for illustrative purposes only and form no part of the claimed design.
